United States Patent Office.

B. B. WILCOX, OF NEW HAVEN, ASSIGNOR TO J. W. NASH, OF MADISON, CONNECTICUT.

Design No. 3,264, dated November 24, 1868.

DESIGN FOR A TRADE-MARK.

The Schedule referred to in these Letters Patent and making part of the same.

To all whom it may concern:

Be it known that I, B. B. WILCOX, of New Haven, in the county of New Haven, and State of Connecticut, have invented a new Design for a Trade-Mark; and I do hereby declare the following, when taken in connection with the accompanying drawing, and the letters of reference marked thereon, to be a full, clear, and exact description of the same, and which said drawing constitutes part of this specification, and represents a side view of the scale, with the design for trade-mark upon the same.

This invention relates to a design for a trade-mark for weighing-scales, and the following is a full description of the said design.

A female figure, blindfolded, and represented as standing upon the earth, holds in one hand a balance, and points with the other hand to a scale standing near her, which said scale is a representation of the scale to which the trade-mark is proposed to be attached.

Having fully described my invention, What I claim as new, and desire to secure by Letters Patent, is—

The design for trade-mark, as herein fully described and illustrated.

B. B. WILCOX.

Witnesses:

A. J. TIBBITTS,
JOHN H. SHUMWAY.
